LOW TEMPERATURE LIQUID CONCENTRATION

Carl Berger, Dayton, Ohio, assignor to The Commonwealth Engineering Company of Ohio, Dayton, Ohio, a corporation of Ohio

Application July 27, 1953, Serial No. 370,534

2 Claims. (Cl. 62—124)

This invention relates to a method of concentrating liquid-bearing substances and to apparatus therefor.

The concentration of solutions by the slow freezing of the solvent from the solution is known; efficient processes and apparatus for effecting the same are described in United States Patents 2,552,525 and 2,559,205 to E. P. Wenzelberger, for example.

It is a primary object of this invention to describe an improved process for the low temperature concentration of liquid-bearing substances.

It is an important object of this invention to describe a system for low temperature concentration of liquid-bearing substances which system requires only very simple apparatus.

The attainment of these and other allied objectives may be exemplified in the case of a solution, for example, by effecting within the solution a slow continuous growth of small crystals of the solvent material; the growth of these crystals in accordance with the invention is achieved by contacting the solution with a solidified body of the solvent and then withdrawing heat from the solution through the said solidified body.

The withdrawal of the heat in the described manner causes that portion of the solution in contact with the solidified body to be the lowest in temperature; accordingly crystal formation occurs at the interface between the solution and the solidified body and the body slowly increases in size as the small crystals form and accumulate; the deposition of the crystals removes solvent from the solution thereby effecting the concentration thereof.

The refrigeration or heat withdrawal is readily controlled and the rate of cooling is such that very tiny crystals form on the solidified body to build it up in substantially a layer-like manner. This avoids entrapment of the mother liquor which itself freezes at a lower temperature and is apparently squeezed away from between the solidified body and the solidifying solvent as growth proceeds. In effect then an advancing front of a solidified body occasions a diminution in the volume of solution while increasing the concentration of the solute therein.

Different solutions will of course have different equilibrium freezing points—that is—temperature at which the solution as a whole freezes and at which the liquid and solid solvent are in equilibrium. Accordingly for optimum conditions of cooling the cooling rate is varied depending upon the equilibrium freezing point. Cooling of the whole of the solution to the equilibrium point is to be avoided; if the cooling is sufficiently slow however the diluent or solvent separates out in solid form as the equilibrium point is approached—thus forming of itself a solution of different concentration having a different and lower equilibrium freezing point. Further it may be noted that since solid diluent and liquid diluent are always in contact no super-cooling occurs; thus in the process of invention no tendency to freeze to a completely solid mass is present.

The apparatus of invention preferably comprises a single tank having the base thereof cooled from the outer

side while the solidified mass of diluent is adjacent the base of the inner side. The base is most suitably of a very heat-conductive metal such as aluminum or copper although the choice of material may vary with the nature of the material to be concentrated. Stainless steel, for example, is preferred for many weakly acid solutions.

The walls of the tank as well as the top are suitably equipped with inlets and outlets as will be more particularly noted hereinafter and are preferably adapted to 10 resist the passage of heat therethrough—thus heat transfer from the liquid in the tank will be substantially solely through the bottom wall and the solidified solvent mass.

The shape of the tank is of some importance as the heat transfer conditions must be such that the surface of the solid diluent exposed to the liquid diluent is always colder than any point in the liquid diluent itself; this prevents solid formation other than at the surface of the solid. Further there is a tendency for crystal growth to begin at the periphery of the solid diluent where it abuts the container walls; accordingly it is frequently desirable to taper the container walls inwardly as this inhibits treeing and assists in the attainment of uniform growth of the solid diluent across the face thereof.

The material of the container walls may influence the temperature point at which crystallization is initiated and may be readily selected of plastic, metal or glass to control the same in desired fashion.

The invention will be more fully understood by reference to the following detailed description and accompanying drawing wherein:

Figure 1 illustrates one embodiment of apparatus useful in the practice of the invention;

Figure 2 illustrates one arrangement of heat transfer apparatus useful in a structure such as that shown in 35 Figure 1;

Figure 3 is another arrangement of heat transfer apparatus;

Figure 4 is another arrangement of heat transfer apparatus in which the coolant directly contacts a heat transfer plate; and

Figure 5 illustrates one form of bottom wall useful in the structure of Figure 1.

Referring to the drawing there is shown at 1 a tank in the form of an inverted frustum of a cone having an 45 interior chamber 3, a bottom wall 5, side walls 7, 9 and a top 11 which is preferably a continuation of the side walls.

The top 11 is centrally provided with a shaft 13 mounted for rotation in bearings 15 and carrying at the lower end thereof a stirrer blade 17. The other end of the shaft is suitably connected to a driving motor 19 for effecting stirrer blade operation when desired; the stirrer if employed need only extend slightly below the solution surface as it is employed merely to prevent freezing in the upper body of the solution.

Also extending through top 11 is a conduit 21 provided with a valve 23 for the passage of liquids to be concentrated. A valve 25 disposed on the opposite side of the tank top 11 is adapted to automatically control the air pressure within chamber 3.

The side walls 7, 9 are each of metal and conduits 27, 29, 31, 33, 35, 37 pass through each of the walls and each conduit is valved to permit passage of liquid when desired. The conduits are preferably sealed in air-tight relation to the walls as are the conduit 21, valve 25 and shaft 13, and accordingly the spacing 39 may be evacuated to provide against undue heat transmission through the walls. While not normally required the auxiliary apparatus may be heat insulated with respect to the walls to further diminish heat transfer.

The bottom wall 5 is of aluminum and the lower face thereof intimately abuts the upper face 41 of a suitable

refrigeration system 43. This refrigeration system is in no way critical and accordingly is not shown in detail since any of the customary refrigeration apparatus known to the art, such as the usual coils carrying a refrigerated medium, may be employed, and such will normally be selected in accordance with space and temperature conditions of the system.

The bottom 5 is itself supported on an insulation body 43 which is preferably a ring of rubber or similar material vulcanized to the bottom wall 5 and to the walls 7, 9. Secured to the lower face of ring 43 are suitably spaced supporting members as at 45, 47 which maintain the whole unit above floor level.

As shown in the figure the tank is partially filled with orange juice to just above the level 49 and is in contact with a block of ice 51 supported on the bottom 5. The ice 51 is first preferably formed by placing a small quantity of water into the tank and freezing the same by withdrawing heat through bottom 5 by means of the refrigeration system. The valves 31, 37 are of course closed at this time.

The orange juice is then admitted (with valves 27, 29, 33 and 35 also closed) through the conduit 21 and valve 23. The juice is preferably cooled prior to entry to about 5-10 degrees above the freezing point for the solution; in the case of natural juice wherein ice formation would normally begin at about 28° F. the juice temperature upon entry to chamber 3 may suitably be 34-36° F. which is also above the ice temperature.

The refrigeration system preferably continues to operate during the admission of the juice and since substantially no heat transfer occurs through the lateral walls the coldest juice at any given time will be that in contact with the ice. Accordingly ice crystal formation begins usually at the juncture of the ice and the solution; the sloping side of wall 9 inhibits treeling and the ice formation takes place in substantially flat thin layers as indicated by the dotted line 53.

Control of this layer formation for various solutions may be exercised by varying the shape of the walls, the area of contact of bottom wall 5 with the refrigerating plate 41 or more suitably by varying the cross-sectional shape or material of plate or wall 5.

Thus as shown in Figure 2 the refrigeration system may comprise an upper layer 61 of aluminum, a layer 63 of nickel and the cooling coils 65 for the passage of refrigerant. In this instance the layer 61 in the refrigeration system would be placed directly against bottom wall 5 and the net effect would be to decrease the heat transfer capacity over that of simply a thin aluminum wall.

Figure 3 illustrates an arrangement in which a layer 67 of aluminum is contacted by small granules of finely divided copper 71 in which are embedded the cooling coils 69 supported by a metallic (aluminum) closure member 73. The finely divided copper assists in attaining a very uniform overall temperature condition at the layer 67 which contacts the bottom wall 5 of the tank.

Figure 4 illustrates an arrangement in which a liquid coolant is flowed through an inlet 77 to contact plate 75 in the spacing 81, the liquid exiting through outlet 79. Insulating material 83 prevents undue loss of heat from the coolant.

Figure 5 illustrates an embodiment for use as the lower wall of the tank the aluminum or copper member 85 being cupped to control the advance of the ice. The control is effective since the original layer of solid solvent will be greater at the center than at the thus decreasing heat transfer through the center. Alternatively if desired the bottom wall may be convex or the thickness of the material in the wall and the nature of the material may be varied to control heat withdrawal from the solution.

As the withdrawal of heat proceeds (referring again to Figure 1) the body of ice increases in thickness incrementally and simultaneously the juice is concentrated. The concentration may proceed to any desired extent, as

for example, to the point at which the top of the ice is just below the aligned conduits 29, 35 when the refrigeration apparatus is shut off. The valves of these conduits 29, 35 may then be opened and the concentrated liquid drained from the chamber.

When drainage has been completed and with the valves 29, 35 again closed steam may be introduced through inlet valve 55 to the spacing 39 and circulated to cause a melting or partial melting of the ice mass. If complete melting is desired the water may be drained off through valves (not shown) to completely empty the chamber. If partial melting is desired valves 31, 37 may be utilized to draw off the solvent.

In given instances it may be desirable to concentrate the juice to a further degree, for example, until the ice mass is just below valves 27, 33. After withdrawal of the concentrated juice the ice may then only be partially melted, that is to the level of valves 29, 35 whereupon the water may be drawn off to waste through these latter valves. The ice remaining may then serve as the base for a further concentration process in the same manner as hereinbefore described.

Ordinarily in the freezing process the natural heat diffusion currents which arise as heat is withdrawn are sufficient to circulate the liquid over the ice mass. In such case the stirrer blade 17 is not operated. In the event however that a particular material does not circulate readily, or when the concentrate becomes viscous, the stirrer may be slowly operated to cause slow movement of the liquid.

The process and apparatus while described with particular reference to a fruit juice is readily applicable to organic solutions such as pyridine in acetophenone and so forth; the solvent need not be water and various adaptations of the apparatus described may be made to permit of very low temperature operation.

It will be understood that this invention is susceptible to modification in order to adopt it to different usages and conditions and accordingly, it is desired to comprehend such modifications within this invention as may fall within the scope of the appended claims.

I claim:

1. In apparatus for freeze concentration of materials a tank having a heat conductive bottom wall and upwardly inwardly tapering side walls, means insulating the interior of the tank from the atmosphere along the side walls, means cooperable with the bottom wall of the tank for withdrawing heat from the tank through the bottom wall thereof, a plurality of drain conduits in vertical relation extending from the tank to the exterior, and inlet conduit means for the entry to the tank of material to be concentrated, the bottom wall of the tank being adapted to support a volume of liquid interiorly of the tank.

2. A method of concentrating a liquid bearing material comprising a diluent by freezing out of the diluent which comprises the steps of retaining a small quantity of the diluent on a horizontal surface and freezing the same to a solid mass, maintaining the solid mass of diluent frozen and confining a relatively large volume of the liquid bearing material on top of the solidified mass of the diluent above the interface surface portion thereof, withdrawing heat from the liquid bearing material substantially only through the solid mass of diluent while maintaining the temperature of the body of liquid bearing material above its solidification point, stirring the liquid bearing material adjacent the surface of the material but remote from the interface, lowering the temperature of the liquid bearing material at the interface to the freezing point and below that of the volume remote from the interface to cause diluent at the interface to solidify in small substantially pure crystals on the body of solid diluent and to cause the solid diluent to increase and to advance into the volume of the liquid bearing material to provide a new interface whereby the material is concentrated, and thereafter with-

drawing the concentrated liquid bearing material from the solidified diluent.
